UNITED STATES PATENT OFFICE.

HERVE C. MANON, JAMES A. BROMLEY, AND JOHN Z. BROMLEY, OF WASHINGTON,
PENNSYLVANIA.

AMALGAMATOR.

Application filed June 11, 1928. Serial No. 284,600.

The invention relates to amalgamators for use by dentists primarily, and it is one object of said invention to provide a very simple, inexpensive, durable and efficient construction which is actuated by compressed air, for the purpose of vibrating a capsule or the like containing the ingredients to be mixed.

Another object of the invention is to provide a unique holder for the capsule or other container.

With the foregoing in view, the invention resides in the novel subject matter herein-after described and claimed, description being accomplished by reference to the accompanying drawing.

Figs. 1 and 2 are vertical sectional views partly in elevation showing the reciprocatory plunger and the capsule holder carried thereby, in their lowered and raised positions respectively.

Fig. 3 is a horizontal section on line 3—3 of Fig. 1.

The drawing above briefly described illustrates the preferred form of construction and while this construction will be herein specifically explained, it is to be understood that within the scope of the invention as claimed, variations may be made.

The numeral 5 on the drawing denotes a body which comprises a flat-bottomed, preferably circular base 6 to rest on a laboratory table, shelf or other desired support, and a post 7 integral with and rising from the center of said base. The post and base are jointly formed with a vertical bore 8 whose lower end is closed by a screw plug 9, while its upper end 10 is reduced and opens through the upper end of said post. A plunger 11 is slidably mounted in the bore 8 and embodies a reduced rod portion 12 passing slidably through the reduced end 10 of said bore, the upper end of said rod portion being provided with a holder 13 for a capsule or the like 14, to contain the ingredients to be mixed. The plunger 11 and the body 5 are provided with co-acting means for utilizing compressed air or other fluid under pressure, to effect vertical reciprocation of said plunger to similarly reciprocate the capsule holder 13. Preferably, these co-acting means are of the character now to be described.

Body 5 is formed with an inlet port 15 for compressed air or other fluid under pressure, one end of said port being threaded at 16 for

connection with an air supply hose or pipe, while the other end 17 of said port opens into the bore 8, centrally between the ends of the latter. An upper port 18 leads from a point somewhat above the port end 17, into the upper end of the bore 8, and a lower port 19 leads from a point somewhat below said port end 17, to the lower end of said bore 8. Near its upper end, this bore is provided with an exhaust port 20 and a similar port 21 is located near the lower end of said bore. The body portion of the plunger 11 is reduced centrally as denoted at 22, so that when the plunger is in the position of Fig. 1, the fluid under pressure from the port 15 may pass around this reduced portion 22 and through the port 19, into the space under said plunger, thus forcing the latter upwardly to the position of Fig. 2. During ascent of the plunger, any fluid above it, is exhausted through the port 20. By the time the plunger reaches the position disclosed in Fig. 2, the space around its reduced portion 22, places the ports 15—18 in communication, so that the fluid pressure then enters the bore above the plunger to again drive the latter downwardly, fluid from the lower portion of the bore being then exhausted through the port 21. It will thus be seen that by using the compressed air already accessible in the dentist's laboratory, the amalgamator may be rapidly operated. The device is efficient and produces quick results, and it possesses practically no parts to get out of order and cause trouble. As the movement of the plunger 11 is strictly vertical, it has practically no tendency to cause wear between itself and the bore, and danger of battering the ends of the bore or the ends of the plunger body, is prevented, due to the fact that an air cushion is formed in each end of the bore to yieldably check the movement of the plunger.

In the preferred construction herein disclosed, a metal sleeve 23 is threaded upon the upper end of the rod portion 12, the upper end of said sleeve being provided with a head 24 having a socket 25 at its upper end to receive the lower end of the capsule 14. A C-shaped strip 26 of spring metal is formed with an opening 27 in its lower end, receiving the sleeve 23, and said lower end of the strip is clamped against the head 24, by a collar 28. This collar surrounds the sleeve 23 and the lower end of the latter is upset to secure the collar and spring in place. A second head 110

30 contacts with the lower side of the upper end of the spring 26, the lower side of said head being formed with a socket 31 co-operable with the socket 25 in holding the capsule 5 or the like 14. Head 30 is provided with an upstanding stud 34 which passes through an opening 33 in the upper end of the strip 26, said stud being upset to secure the head and strip together. This strip may be readily 10 sprung to permit separation of the heads 24—30 to the desired extent, for inserting or removing the capsule or other container 14, and the inherent resiliency of this strip then holds the heads against the capsule to retain 15 the latter in place while it is being vibrated by the reciprocatory plunger.

Attention is invited to the following characteristics of the device:—The base 6 is thick and heavy and projects horizontally in all 20 directions from the post 7 to prevent tilting of said base and post under the influence of gravity, without the necessity of fastening the base to the laboratory table or the like upon which it is used, permitting it to be 25 moved from one place to another as may be most convenient. The plunger body 11 is of considerably more than half the length of the bore 8 so that when it is raised as seen in Fig. 2, it does not materially raise the center of 30 mass and consequently has no tendency to cause the base and the post to tilt. Then too, the connection 16 for the compressed air hose, is disposed in the base 6 so that the hose may rest upon the laboratory table or the like in 35 such position that its weight will have no tendency to cause the entire device to tip over. Furthermore, the weight of the post and the base are such that they will not be vibrated by reciprocation of the plunger and consequently the entire device will not creep 40 upon the supporting surface. Attention is further invited to the fact that the post 7 and the base 6 are jointly formed with the bore 8. This permits the use of the advantageous 45 vertically elongated plunger without the necessity of extending the post so high as to possibly cause the structure to become top-heavy with the plunger body in its raised position. Then too, the plunger body 11 is of 50 much less diameter than the post 7, so that the mass of the stationary part of the amalgamator cannot be vibrated by reciprocation of the comparatively light plunger.

It will be seen from the foregoing that a very simple, efficient, durable and generally 55 desirable device has been provided, and while the details disclosed are preferred as above stated, attention is again invited to the fact that within the scope of the invention as claimed, variations may be made.

We claim:—

1. In a dental amalgamator, a short vertical post, a thick heavy base joined rigidly to the lower end of said post and projecting horizontally in all directions therefrom to anchor said post against tilting when the base rests upon and is free of attachment to a supporting surface, said base and post jointly having a plunger-receiving bore which extends substantially to and is closed at the bottom of said base but is open at the upper end of said post, a plunger body slidable in said bore and of much less diameter than said post, said body being of considerably more than half the length of said bore, whereby in its raised position, the body will not materially raise the center of mass with danger of causing tilting of the base and post, and a stem rising from said plunger body and projecting above the post, said stem being provided with a capsule holder, said base and post being provided with portage for compressed air to reciprocate the plunger, said portage having a connection for an air supply hose, said connection being disposed at said base whereby the hose will have no tendency to tilt the base and post.

2. In an amalgamator, a shaker rod, a sleeve threaded on one end of said rod and having a head at its outer end, the outer side 90 of said head being formed with a socket, a C-shaped spring metal strip having an opening in one end receiving said sleeve, a collar on the sleeve between which and said head said one end of said spring is clamped, the 95 inner end of the sleeve being upset to hold said collar in place, and a second head secured to the other end of the spring and formed with a socket opening toward the first named socket.

In testimony whereof we have hereunto affixed our signatures.
